CROWN CAP

Halford E. Brockett, Elmhurst, Ill., assignor to Continental Can Company, Inc., New York, N.Y., a corporation of New York

Filed July 24, 1964, Ser. No. 81,002

Term of patent 14 years

(Cl. D58—26)

FIG.1

The characteristic features of my design reside in a pull tab or tear strip element which covers the major portion of the top of the crown cap and which is decorated with the specific pattern of ribs, all as shown.

I claim:

The ornamental design for a crown cap, as shown and described.
